UNITED STATES PATENT OFFICE

2,097,268

STEAM GENERATOR

Simon C. Best, Williamsport, Pa., assignor to
 E. Keeler Company, Williamsport, Pa., a corporation of Pennsylvania

Application November 19, 1935, Serial No. 50,534

19 Claims. (Cl. 122—347)

This invention relates to improvements in steam generators of the type which is adaptable to the utilization of combustible fuels in solid, liquid, or gaseous form, the burning of which produces heat to generate steam from water, which has a rapid, positive, and natural circulation.

Whereas the objects of the invention are numerous, one of the more important objects resides in a steam generator consisting of a single compact structure in which the radiant heat and air infiltration losses are reduced to a minimum, space is saved, the initial cost of a masonry brick enclosing structure is eliminated, and the maintenance of furnace refractories is greatly reduced, thus making more practical and economical for the generation of steam, efficient heat transfer and recovery devices of original design and arrangement.

Other objects of the invention are as follows: to provide a steam generator which may be operated with high working pressure and temperatures, thus permitting maximum overloads without deterioration and excessive maintenance since heat absorbing surfaces shield or screen certain, or all enclosing walls from the hot gases of combustion; to provide a definite and positive water circulation by reason of a constant and adequate supply of relatively cooler water and by reason of the fact that all circulating tubes are substantially vertical; to provide a steam generator unit containing a maximum of steam generating surfaces in a minimum of space; and to provide a water line which is relatively low and which is steady at all ratings because of the balanced ring flow circulation.

Another object of the invention consists of a steam generator wherein the combustion space of the integral boiler and furnace is formed by means of water cooled furnace side walls, a refractory or water cooled bridge wall, and a refractory or water cooled front wall, the water wall cooling tubes forming secondary but highly efficient steam generating elements which constitute an integral part of the boiler and are so connected therewith through headers as to promote natural ring flow circulation of the water.

A further object of the invention is the provision of a steam generator wherein all water cooling tubes as well as the water wall headers and connecting tube circulators are contained entirely within the casing or setting and are swept constantly by the hot gases of combustion.

A further object resides in a steam generator in which all connections between integral parts are expanded metal to metal joints, thereby

eliminating gaskets and bolted or screw joints, and wherein the various parts are so arranged as to be readily accessible for repair or replacement purposes.

A further object of the invention resides in a steam generator having the above features which may have incorporated therein an economizer, or superheater, or both, without changes in construction or rearrangement of the parts.

A still further object is to provide a steam generator of such design as to preclude the accumulation of any material amount of soot and dirt, and which retards the adhesion of fused particles of ash. Furthermore, the novel construction and arrangement of parts facilitates the cleaning of the heating surfaces of the generator by a lesser number of soot blower elements than is required for the cleaning of corresponding size generators heretofore designed.

With these and other objects in view, the invention resides in the novel construction, combination and arrangement of parts, the essential features of which are hereinafter fully described in the following specification, are set forth in the appended claims, and are illustrated in the accompanying drawings, in which:

Figure 1 is a front elevational view of my improved steam generator.

Figure 2 is a rear elevational view of the same.

Figure 3 is a vertical longitudinal sectional view.

Figure 4 is a horizontal sectional view taken on a plane just above the soot blower shown in Figure 3.

Figure 5 is a horizontal sectional view taken on the plane just below the bottom of the lower drum.

Figure 26 is a detail vertical transverse sectional view on the line 26—26 of Figure 24.

40 Figure 27 is a still further modified form of steam generator.

45 Figure 28 is a detail vertical sectional view of a modified form of front water wall header.

Referring to the drawings by reference characters, the numeral 10 designates a foundation on which the steam generator is set and which generator includes a four side wall and top wall structure or setting consisting of a solid refractory front wall 11, refractory side walls 12—12, an insulated rear wall 13, and a refractory roof or top wall 14. The front, side, and top walls are covered by a thickness of insulation 15, and these walls are enclosed in an outer steel casing 16.

50 Rising upwardly within the walled structure and extending transversely thereof is a refractory bridge wall 17, the same terminating well below the roof 14, but extending well above the plane of the grate 18 located forward of the bridge wall. The bridge wall divides the interior of the wall structure into a forward combustion chamber 19, and a rear gas flow compartment 20. The chamber 19 and compartment 20 communicate by reason of the space between the top of the bridge wall and the roof of the structure. The combustion chamber 19 may be fired by any of the conventional methods, but in the drawings I have 55 shown an automatic coal stoker 21.

Extending the length of the wall structure and supported independently thereof at the front and rear by steel frames, is a top water and steam collecting drum 22. The drum 22 is disposed centrally of the wall structure at the top thereof, and the exposed portions of the drum are covered by insulating material and the outer steel casing. Extending inwardly from the front end of the drum 22 is a water feed pipe 23, the same terminating adjacent the rear end thereof, which

rear end is the coolest portion of the drum by reason of the fact that the heated gases from the furnace or combustion chamber escape from the generator at the top rear through the smoke outlet 24.

5 Mounted within and adjacent the bottom of the compartment 20 and extending from a point adjacent the bridge wall 17 to and through the rear wall 13 is a bottom water drum 25, the same being disposed in vertical alignment with the top 10 drum 22. Boiler circulating tubes 26 which may be termed primary heating elements connect the water and steam drum 22 and the water drum 25. The tubes 26 are arranged in rows and are staggered with respect to the general direction of the 15 gas flow as shown in Figure 4 and which will be more fully explained hereinafter. Certain of the outermost tubes or primary heating elements designated 26' extend downwardly along the refractory side walls and although they connect 20 with the lower drum 25, they act as water wall cooling tubes.

25 In the form of my steam generator shown in Figures 1 to 12 inclusive, I employ three spaced baffles 27, in the compartment 20, the end two of 30 which extend downward from the roof while the intermediate baffle extends upward from the floor. The end baffles terminate short of the top of the drum 25 and the intermediate baffle terminates short of the top drum 22 and coact to 35 provide an undulant passage for the smoke in its passage from the combustion chamber 19 to the smoke outlet 24. The three lapping baffles extend transversely of the compartment 20 and provide the generator unit with a four pass boiler, 40 the circulation path of the heated gases being shown by arrows in Figure 3 of the drawings. In a modification shown hereinafter in Figure 13, the generator unit includes but two baffles which provide a three pass boiler with the escape of 45 smoke and gases at the bottom rear of the structure and which arrangement may be desirable under various conditions.

55 Water wall tube headers 28 extend substantially the length of the side walls 12—12 on substantially the same horizontal level as the grate line of the furnace. Water circulating tubes 29 connect the bottom water drum 25 with the water wall headers at the rear end thereof, the said tubes 29 extending from the drum 25 as best seen 60 in Figure 6. The rows of tubes 26 disposed rearwardly of the plane of the end baffle 27 are termed downcomers and constitute a rear group 65 A of primary heating elements while those rows of tubes 26 forward of the intermediate baffle 27 constitute a group B of upcomers or primary heating elements.

Furnace water wall tubes 30 connect the top 70 water and steam drum 22 with the headers 28 and are disposed adjacent the inside of the refractory side walls. The outside rear boiler tubes are distinguished from the other boiler tubes 26 and 26' by the numeral 30a and they function as downcomers or circulating tubes which connect the rear ends of the side wall headers 28 with the 75 upper water and steam drum 22. These tubes 30 and 30a connect the headers with the drum 22 forward and rearward respectively of the group of outer intermediate circulating tubes 26'. The tubes 30 serve as heating elements and convey 80 the water from the headers back up to the water and steam drum 22. The top ends of the water wall tubes 30, the outside rear boiler tubes 30a and the outer circulating tubes 26' are curved 85 inwardly and join the drum 22 on a plane ap-

proximately in horizontal alinement with the axis of the drum, whereas the primary circulating tubes 26 connect with the drum 22 at its under side. The lower ends of the tubes 26 connect 5 with the lower drum 25 at a point above the plane of its horizontal axis while the outermost group of tubes 26' connect at or on a plane of said horizontal axis.

In this construction of the steam generator 10 and the modifications to follow, all joints between integral parts are expanded metal to metal, thereby eliminating gaskets, and bolted or screw joints.

The bottom ends of the water wall tubes 30 15 which are disposed in the furnace compartment 19 and their points of connection with the headers 28 are protected by an armor wall 31 which is cooled by the circulating water in the furnace water wall tubes and headers, all of which constitute an effective clinker chill just above the plane of the grate 18.

The armor wall 31 is constructed of pairs of coacting armor wedge blocks 32 and 33 shown in detail in Figure 10. Each armor block is constructed of cast iron or super-refractory material and has its outer side provided with a concavity 34 which extends the length thereof to snugly fit around approximately one-half the circumference of a water wall tube 30. The inner 30 face of each armor block is inclined as at 35, and when a pair of coacting armor blocks are inserted between a pair of adjacent tubes 30 with their coacting inclined surfaces together, they are wedged into engagement with respective adjacent tubes 30. The wedge blocks rest upon the headers 28 when fully seated in position and by placing them between successive tubes 30, a substantially continuous armor wall 31 is obtained which is easily replaced or renewed from the furnace side.

In operation of the steam generator so far described, it will be understood that any of the conventional firing methods may be employed for providing the necessary heat within the combustion chamber or furnace 19. The generator is supplied with water by the feed pipe 23 which water initially enters the top drum 22 and gravitates to the bottom water drum 25, headers 28 and other elements forming part of the 45 circulating system. The heated gases evolved by combustion within the furnace or combustion chamber 19, radiate heat to the forward group of side water wall cooling tubes 30, and the water cooled surfaces forming the roof of the combustion chamber 19, all of which induces effective steam generation within the secondary heating elements. The gases from the combustion chamber 19 pass therefrom through the passage between the top of the bridge wall 17 and roof into 50 the compartment 20 and act upon the primary heating elements or tubes 26. As previously mentioned the tubes 26 are arranged in rows, staggered with respect to the general direction of the gas flow from the combustion chamber to the 55 gas outlet 24 which is considered a distinctive feature in the general design of curved tube boilers. As the gases pass over, around and between the tubes 26, on their way to the gas outlet 24, the direction of flow is reversed by the gas 60 baffles 27, causing cross flow as well as parallel flow, thus obtaining better diffusion of the gases with resulting better heat absorption by the tubes 26. The baffles 27 cause the gas flow to travel in 65 an undulant path from the combustion chamber 70 19 to the outlet 24.

The baffles 27 concentrate the hot gases on the heating surfaces, and avoid short circuiting of the same. They do not unnecessarily impede the free flow of heated gases evolved by combustion, for these gases freely pass over and around 5 and across the tubes, reversing their direction of flow and becoming thoroughly diffused, thus inducing maximum heat transfer. The heated gases sweep the bottom of the top drum 22 and the top of the lower drum 25 and diminish in 10 temperature as they travel toward the outlet 24. It is the heat subjected to the primary heating tubes 26 by the hot gases as they pass over the bridge wall that causes the water to rise in the upcomer group B. The forward group of tubes 15 26 receive the hottest gases, causing the generation of steam therein, and a decrease in the density of the water, thereby inducing upward circulation.

The circulation of water in the system after 20 heated in the above mentioned manner is forward through the headers 28, upward through the secondary heating elements 26' and furnace water wall tubes 30 to the top drum 22, upward through the front rows of primary heating elements or tubes 26 (group B) to the top drum 22, and downward through the rear rows of tubes 26 (group A) and 30a to the lower drum 25, back to the headers 28 by way of the tubes 29. The rear group of tubes 30a act as downcomers or circulators to assist in providing a direct constant supply of circulating water for water cooling the furnace side walls and thereby inducing a backward and downward circulation in and from the upper drum 22. As previously mentioned, the other or intermediate group of outside tubes 26' 30 connect with the lower drum and the forward tubes of the said group may act as upcomers or steam generating tubes while the rear tubes of said group may function as downcomers or 35 circulating tubes. This system produces in effect, a double ring-flow circulation of water which is positive and rapid, which increases heat absorption, and which maintains a steady water line. With the steam outlet 36 located adjacent the 40 rear of the top water and steam drum 22, the necessity of internal and steam water baffles usually provided within the water and steam drum is eliminated.

By constructing a steam generator unit in the 45 manner hereinbefore set forth wherein all tubes are substantially upright and the gas baffles are vertical, the accumulation of any material amount of soot and dirt thereon is eliminated and the adhesion thereto of fused particles of ash is 50 retarded. This construction and arrangement of parts enables the use of but a single mechanical soot blower element in small size generator units and facilitates the cleaning of larger units by a 55 lesser number of mechanical soot blower elements 60 than now used in connection with other corresponding size generator units. In the drawings, one mechanical soot blower element 37 is shown, which extends inwardly through the rear wall 13 and terminates adjacent the bridge wall 17. The 65 soot blower element 37 passes centrally through the right and left banks of tubes 26 as best seen in Figure 6 of the drawings, and through the baffles 27. The soot blower element is supported by bearings which are attached to the inner tubes 70 of certain rows of primary steam generating tubes or elements 26 at several points throughout the length of the element, as required. The soot blower element is provided with nozzles which direct jets of steam between adjacent rows of 75

tubes, radially from and at right angles to the element as it is rotated. The mechanical soot blower element such as shown at 37 is old in the art so that a detailed description of the same 5 is not believed necessary.

A blow off pipe 38 extends from the bottom rear of the water drum 25 and connects with a pipe line 39, and arranged in the pipe 38 is a blow off valve 40. Blow off pipes 41 also extend from the bottom 10 rear of the two headers 28 and are joined with the blow off pipe line 39, exteriorly of the generator unit casing. Blow off valves 42 are arranged in the blow off pipes 41. All of the valves 40 and 42 are exteriorly disposed relative to the 15 generator casing. A blow-off valve 43 is also arranged in the pipe line 39. One or both ends of the water wall headers 28 may be provided with master manhole openings.

Extending from the top of the top drum 22 20 adjacent the outlet 24 and rearward of the safety valve outlet nozzle 36 is a steam outlet nozzle or coupling 44. Suspended within the top drum 22 above the water level thereof is a dry steam pan or pipe 45, the same being supported at its ends 25 by brackets 46 extending downwardly from the top of the drum. The dry steam pan or pipe 45 consists of a metal cylinder having perforations 47 along the top thereof and a stack 48 rising upwardly into the nozzle or coupling 44. The 30 dry steam pan or pipe is suspended in a slightly inclined position so that the stack end is higher than the other end. The lower end has two drain openings 49 in the bottom thereof. The dry steam pan or pipe extends to the rear end of the top 35 drum which is swept by the heated gases as they pass to the chimney outlet 24. Dry steam from the drum 22 enters the dry pan through the openings 47 from where it passes out through the stack 48 to the superheater now to be explained.

40 Connected to the nozzle or connector 44 is one end of a pipe 50, the same extending downwardly adjacent the exterior of one of the side walls 12 and terminating approximately midway thereof and to which a short horizontally disposed pipe or manifold 51 is connected by means of an elbow 52. The free end of the pipe section 51 is closed and joined to this pipe section 51 are one end of superheater tubes or elements 53. The tubes or elements 53 extend transversely 50 within the compartment 20 just rearward of the bridge wall and are looped and extended outward beyond the same side wall from which they enter the compartment. A coupling pipe section or manifold 54 receives the return ends of the superheater tubes or elements and to which a pipe line may be connected to carry the superheated steam to any device intended to receive the same. To accommodate the superheater tubes or elements 53 within the compartment 20, adjacent 55 rows of the group of tubes 30 and circulating tubes 26 are spread apart as seen by reference to Figure 3 of the drawings. The superheater tubes or elements 53 are subjected to the intense heat of the heated gases after passing over the bridge wall 17, and the heat therefrom transforms the dry steam from the steam drum 22 into superheated steam.

In Figure 13 of the drawings, there is shown a modified construction of steam generator 70 wherein the principle of operation is the same as that previously described, but which I term a three pass boiler with the heated gases expelled from the rear bottom instead of at the rear top. The setting is substantially the same as that previously described and a description of the same

is not believed necessary, thus similar reference characters hereinbefore referred to will designate like parts in Figure 13.

In Figure 13, the numeral 54 designates the top water and steam drum, 55 the lower water drum, 5 and 56 the circulating tubes or primary heating elements connecting the drums 54 and 55. The tubes 56 are divided into three groups by a pair of spaced baffles 57, one extending downwardly and the other extending upwardly. The groups are 10 identified as a rear upcomer group C, an intermediate downcomer group D, and a front upcomer group E. The heated gases of combustion take the path indicated by the arrows, and are exhausted through an outlet conduit 58 at the 15 bottom rear of the setting. Feed water enters the lower drum 55 at the rear through a feed pipe 59.

The interior of the drum 55 is divided into two 20 separate compartments by a transverse partition 60, the C group of tubes 56 entering the rear compartment of the drum 55 and the groups D and E of said tubes entering the forward compartment thereof. The group C and rear compartment of the drum 55 constitutes an integral 25 economizer by which feed water entering the generator may be preheated by the gases of combustion before rising to the water and steam drum 54 through the upcomer group of tubes C.

The side wall headers 61 in Figure 13 extend 30 rearwardly from the front wall of the setting but terminate short of the rear thereof, and water wall tubes 62 connect them with the water and steam drum 54. Water wall circulating tubes 63 connect the front end of the lower drum 55 35 with the side wall headers 61.

The circulation within the steam generator shown in Figure 13 is as follows: Feed water enters the rear of the bottom drum through the feed pipe 59 then upward through C group of 40 tubes 56 to the water and steam drum. From the water and steam drum 54, downwardly through group D of connecting tubes 56 to lower drum 55, through tubes 63 to headers 61, forwardly through the headers, thence upwardly through 45 water wall tubes 62. The front group E of tubes 56 act to convey heated water from the front end of the drum 55 to the top drum 54, for all these tubes are swept by the heated gases immediately after the gases pass over the bridge 50 wall 17.

In Figure 14 there is shown a modified form of water wall header 64, the forward end of which is downwardly and rearwardly inclined to follow the drop of an inclined multiple retort 55 underfeed stoker 65. The lower ends of the water wall tubes 66 extend at right angle to the angle of inclination of the header 64 but said lower ends are provided with bends so that the major length of the tubes 66 may be vertically 60 disposed.

In Figure 15, there is illustrated a modified form of integral superheater which includes superheated tubes 67 which extend radially from the top of the water and steam drum 54', and 65 downwardly through the roof covering into the boiler proper where they are extended horizontally and transversely as at 68, then looped as at 69, and extended horizontally and transversely as at 70. The portions 70 of the superheater tubes 70 extend through a side wall of the setting and radially connect with a superheater header 71. The superheater tubes may be located between adjacent rows of primary circulating tubes 56' where they will be swept by the hot gases from 75

the combustion chamber, or they may be located forward of the front row of tubes 56' adjacent the bridge wall and thus exposed to the radiant heat of the furnace. By the construction shown, 5 it will be seen that a minimum amount of steam conveying pipes requiring insulation are exposed. All joints in the superheater are expanded metal to metal thereby eliminating all pipe joints.

In Figures 16 and 17, the numeral 72 designates a front furnace wall having fire door openings 73 therein. Supported by the setting of the front wall and extending transversely thereof directly above the fire door openings, is a front water wall header 74, one or both ends of which 15 can be provided with a master hand hole cover 75 for access thereto. Opposite ends of the front water wall header are connected with the side water wall headers 76 by vertical pipes or tubes 77. Extending upwardly from the front water 20 wall header 74 are front water wall tubes 78 which radially connect with the lower periphery of the top water and steam drum 79. The side water wall tubes 80 extend upwardly from the side wall headers 76 and enter opposite sides of 25 the drum 79 in the same manner as described in the preceding forms of the invention.

From the construction shown in Figures 16 and 17, it will be seen that the front water wall header 74 and front water wall tubes 78 are arranged in 30 the boiler circulation for they are supplied with water from the side wall headers. Also, the front water wall header 74 not only provides a water circulating medium for the front water wall tubes 78, but it also forms water cooled fire door arches 35 which eliminate the maintenance of the usual refractory arches.

Figures 18 and 19 illustrate a water cooled bridge wall which consists of a refractory tile or monolithic baffle 80, the bottom of which terminates substantially on the plane of the top of the side wall headers 81. Extending transversely and disposed directly beneath the baffle 80 is a header 82, the ends of which terminate in spaced relation to the side wall headers 81 to 45 enable lengthwise expansion of the header 82. The header 82 is connected to the front end of the lower water drum 83 by tube nipple connections 84 for supplying water to the header 82. Extending upwardly from the header 82 and 50 passing through the baffle 80, are bridge wall water cooling tubes 85, the same connecting at their top ends to the bottom periphery of the upper water and steam drum 86. By this construction of bridge wall, the baffle 80 deflects the 55 radiant heat of the furnace and hot gases of combustion around and away from the front end of the lower drum 83, and the highly heated refractory material will also serve to aid ignition and complete combustion of the furnace fuel. The header 84 and water cooled bridge wall also 60 provide a non-clinker forming back for a solid fuel bed. Cast iron water wall armor may be used at the bottom of the refractory bridge wall baffle on top of header 82 the same as previously 65 described so as to form a clinker chill. Furthermore, the water cooled bridge wall is an integral part of the boiler and adds effective steam generation surface thereto while protecting the front head of the lower drum 83 and making the head 70 readily accessible for cleaning purposes and periodic inspection through openings 87 in a transverse partition 88 which closes the space between the floor of the setting and the header 82. The 75 openings 87 are normally closed by doors 89.

Figures 20 and 21 illustrate a modified form of

water cooled bridge wall, and those parts which are identical with corresponding parts shown in Figures 18 and 19 are identified by like reference characters. However, in this form, the refractory partition is designated 80' and extends 5 upwardly and forwardly into the furnace or combustion chamber 90. The bridge wall water cooling tubes 85' pass through the upwardly and forwardly curved partition and continue forwardly and upwardly and connect radially with the top 10 drum 86 adjacent the front wall 91 of the boiler setting in the same manner as previously described. The functions of the tube header 82, connecting tube nipples 84 and drum 83 are the same as described in the preceding form of water 15 cooled bridge wall, but in addition to these functions, the water cooling tubes 85' constitute a water cooling arch for the furnace 90, for they carry the water from the header 82 upwardly and forwardly. The refractory arch 80' aids in igniting and effecting complete combustion of the fuel, while the heated gases pass through the spaces between the arch cooling tubes 85' which in this instance also act as a slag screen.

In Figures 22 and 23 there is shown a steam 25 generator similar to that shown in Figures 1 to 12 with the exception of a modified water cooled bridge wall, arch, slag screen, superheater, and to show how the side wall headers may be dropped to a plane below the bottom water drum. 30 The refractory bridge wall in this form is designated 92 and after rising vertically a sufficient distance to shield the bottom drum and deflect gases the same extends forwardly and upwardly, and terminates in an angularly upwardly extension 35 93. A header 94 extends transversely beneath the lower drum and connects therewith through tubes 95. Water cooling tubes 96 extend from the header 94 and follow the contour of the bridge wall, thence forwardly through the 40 front wall of the setting where they connect with a header 97, which in turn is connected by tubes 98 to the top water and steam drum. The water cooling tubes 96 serve the same purposes as the bridge wall water cooling tubes 85 and 85' here- 45 inbefore described.

The superheater tubes 99 extend inwardly of the furnace from the headers 100 and 101 disposed exteriorly of the front wall and are interposed between the roof of the setting and 50 the arched portion of the water cooling bridge wall tubes 96. The steam inlet header 100 is connected to a pipe 102 which leads to the steam outlet nozzle on the top of the top water and steam drum. Depending hangers or brackets 103 55 support the inner looped ends of the superheater tubes. The heated gases of combustion sweep the superheater tubes 99 as they pass through the water cooling tubes 96 and rearwardly over the arched bridge wall 92 from 60 the furnace compartment.

In Figures 24 to 26 a generator constructed on the same general principle as that hereinbefore described is illustrated but the structural design is somewhat different. This type 65 of steam generator has been designed for operation by the use of pulverized fuel and includes a low refractory end wall 104 having a burner opening 105 therein, while a water cooled bridge wall 106 extends inwardly and upwardly therefrom. The bottom water drum 107 is disposed directly above the wall 104 and connects with the top drum 108 by the primary circulating tubes 109, swept by the heated gases by reason 70 of the circuitous path created by the spaced stag- 75

gered baffles 110. The side water wall headers 111 are disposed adjacent the floor or bottom of the combustion chamber 112 and connecting the bottom drum 107 with the headers, are connecting tubes 113. Water wall circulating tubes 114 connect the headers 111 with the top drum 108. Alternate tubes 114 have their lower ends extended across the bottom of the furnace compartment 112 at an inclined angle as at 115 to connect with the header on the side opposite to which the said tubes rise as best seen in Figure 26. A smoke outlet 116 is provided in the top of the front end wall. The circulation is the same as that described in the previous designs 15 of boilers, but in this design the water wall cooling tubes 114 also form a water cooled floor for the combustion chamber 112. The crossing portions 115 of these tubes are inclined to promote circulation and for ease in removing soot and 20 dirt accumulation within the combustion chamber.

In Figure 27 a still further modified design of generator has been illustrated and which is quite similar to the design shown in the preceding 25 form with the exception that in this instance, the side wall headers are on the plane with the bottom drum and the front wall 116 of the setting is provided with vertical water cooling tubes 117, the upper ends of which connect with the top water and steam drum in the same manner as previously described. The lower ends of the tubes 117 extend outwardly through the front wall at a down angle and connect with a front water wall header 118 disposed 30 exteriorly of the front wall 116. A header 119 extends transversely of the exterior of the rear wall 120 and is disposed on a plane below that of the header 118. Tubes 121 connect the headers 118 and 119 and the said tubes extend 35 in a rearwardly inclined direction to provide a water cooled floor for the combustion chamber 122. Vertical tubes 123 connect the header 119 with the bottom water drum and the circulation of water is from the bottom drum, down 40 through the tubes 123, header 119, tubes 121, header 118, tubes 117 to the top drum. The side walls below the side water wall headers may be air cooled, the circulating air providing 45 pre-heated air for combustion.

In Figure 28, a modified form of front wall header 118' is shown and is connected by the lower ends of straight vertical tubes 117' and with the front ends of circulating tubes 121'. The front wall is recessed or stepped in as at 50 124 to receive the header 118'. This construction eliminates the angular bend in the front water wall tubes shown in Figure 27.

From the foregoing description taken in connection with the accompanying drawings, it will 55 be understood that this design of boiler or generator provides a double ring-flow water circulation with only two drums. One of the principal paths of circulation cools the furnace while at the same time steam is effectively generated. The steam bubbles generated and ascending 60 through the water in the furnace water wall tubes produce a movement in the direction they travel. Also, throughout the several modified designs of steam boilers or generators herein shown and described, all water wall and boiler tubes are vertical substantially throughout their 65 lengths to promote rapid circulation, for it is well recognized that the path promoting the greatest velocity of water is in a directly vertical path.

Whereas, the boiler construction herein shown and described embodies single top and bottom drums, I do not wish to be restricted thereto, for more than one of such drums may be provided if desired without departing from the 5 spirit of the invention.

While I have shown and described several modifications of the invention, I wish it to be understood that such other designs, alterations and changes as come within the scope of 10 the appended claims may be resorted to if desired.

Having thus described the invention, what I claim as new and desire to secure by Letters Patent of the United States, is:— 15

1. In a steam boiler, a setting having side walls, an upper water and steam drum, a lower water drum, headers extending horizontally along said side walls, tubes connecting said lower water drum and said headers, rows of tubes 20 constituting primary heating elements extending downwardly from said upper drum, the rows of tubes being staggered relative to each other, the outermost tubes extending downwardly adjacent said side walls, certain of said outermost 25 tubes being connected to said headers and constituting water circulating tubes to assist in providing a constant supply of circulating water for water cooling said side walls and thereby inducing a water circulation in and from the 30 upper drum, while the other outermost tubes and remaining primary heating tubes are connected to said lower drum and constitute steam generating tubes.

2. In a steam boiler, a setting having side 35 walls, an upper water and steam drum, a lower water drum, headers extending horizontally along said side walls, tubes connecting said lower water drum and said headers, rows of tubes constituting primary heating elements extending 40 downwardly from said upper drum, the rows of tubes being staggered relative to each other, the outermost tubes extending downwardly adjacent said side walls, certain of said outermost 45 tubes being connected to said headers and constituting water circulating tubes to assist in providing a constant supply of circulating water for water cooling said side walls and thereby inducing a water circulation in and from the upper drum, while the other outermost tubes 50 and remaining primary heating tubes are connected to said lower drum and constitute steam generating tubes, a combustion chamber within said setting forward of said rows of tubes, said headers extending into said combustion chamber, 55 and upcomer tubes connected to said headers and rising upwardly within said combustion chamber along the side walls thereof and connecting with said upper water and steam drum.

3. In a steam boiler, a setting having a smoke 60 outlet at the rear thereof, an upper water and steam drum extending the length of said setting, a bridge wall extending transversely of said setting and dividing the interior thereof into a front furnace compartment and a rear primary heating 65 compartment, a lower water drum within said primary heating compartment, side wall headers extending into said furnace compartment and said heating compartment, tubes connecting said lower drum and said side wall headers, water 70 wall tubes rising upwardly from said headers and connected with said upper drum, rows of tubes constituting primary heating elements connecting said upper and lower drums, the primary heating tubes of one row being stag- 75

gered with respect to the tubes of the next adjacent row, and means for directing heated gases originating in said furnace compartment through said primary heating compartment in an undulated path to said smoke outlet whereby the heated gases pass over and through the staggered rows of tubes to effect a breaking up and diffusion of the same.

5. In a steam generator, a setting having fire door openings in the front thereof, a water heating circulating and steam generating system including an upper water and steam drum, side water wall headers, and water wall tubes connecting said upper drum and said side wall headers, a front water wall header extending transversely of the front wall of said setting on the plane of the top of said fire door openings and providing water cooled fire door arches for said fire door openings, tubes connecting the 10 front ends of said side water wall headers with opposite ends of said front wall header, and front water wall tubes rising upwardly from said front water wall header and connected to said upper water and steam drum.

25. 5. In a steam generator, a setting, an upper water and steam drum, a lower water drum, tubes connecting said upper and lower drums, a refractory bridge wall extending transversely of said setting forward of said lower drum, a 30 bridge wall header extending transversely of said setting, tubes connecting said header with said lower water drum, and bridge wall water cooling tubes rising upwardly from said header and being connected to said upper water and steam drum.

6. In a steam generator, a setting, a forwardly curved upwardly extending bridge wall disposed transversely of said setting and dividing the same into a forward combustion chamber and a rear heating chamber, an upper water and steam drum extending the length of said setting, a lower water drum rearward of said bridge wall and connected to said upper drum by tubes, a bridge wall header extending beneath said bridge wall transversely 45 of said setting, tubes connecting said header with said lower drum, and bridge wall water cooling tubes extending through said forwardly curved bridge wall and disposed substantially parallel thereto, said tubes being extended free of said bridge wall and rising upwardly over said combustion chamber and connecting with the forward end of the upper drum.

7. In a steam generator, a setting having a combustion chamber, an upper water and steam drum, a lower water drum, tubes connecting said upper and lower drums, side water wall headers extending along the inside of the side walls of said setting and disposed within said combustion chamber, tubes connecting said lower drum and 50 said side wall headers, side wall water cooling tubes extending downwardly from said upper drum and disposed adjacent the inside of the side walls of said combustion chamber, alternate water cooling tubes on the respective sides of said combustion chamber extending across said chamber and being connected with the headers on the opposite sides of said chamber to provide an integral furnace hearth within said chamber, the other water wall cooling tubes respectively 55 connected to the headers on the sides along which the said water wall cooling tubes depend.

8. A steam generator comprising an insulated setting having a smoke outlet at the rear top thereof, an upper water and steam drum extending the length of said setting, a bridge wall ex-

tending transversely of said setting and dividing the interior thereof into a forward combustion chamber and a rear primary heating compartment, a lower water drum within said heating compartment and disposed behind said bridge wall, rows of boiler tubes connecting said upper drum and said lower drum, the tubes of one row being staggered relative to the tubes of the next adjacent row, water wall headers extending along the inside of the side walls of said setting and disposed within said combustion chamber and primary heating compartment, side water wall tubes connecting said headers with said upper drum, laterally extending tubes connecting the rear portions of said headers with said lower drum, the rearwardly disposed side water wall tubes connecting said headers and upper drum constituting downcomers, and the forward water wall cooling tubes and forward rows of boiler tubes constituting upcomers, and spaced lapping 10 baffles arranged between certain of said rows of boiler tubes for causing the heated gases from said combustion chamber to travel parallel to said upper and lower drums and intermittently parallel to said boiler tubes during the passage of 15 the gases to said smoke outlet.

9. A steam generator comprising in combination, a setting, a furnace within said setting, an upper water and steam drum extending the length of said setting, a lower water drum rearward of 20 said furnace, water circulating headers extending along the side walls of said setting substantially the length thereof, the front ends of which are disposed within said furnace while the rear ends of said headers extend rearward of said furnace, means for circulating feed water from the rear of said upper drum to said lower drum and back to the front of said upper drum through said water circulating headers, and means for returning a portion of the water supplied to said 25 lower drum from the front portion thereof directly to said upper drum, whereby to provide a double ring-like flow of circulating water from said upper drum and return.

10. In a steam boiler, a setting having side 30 walls, an upper water and steam drum, a lower water drum, headers extending forwardly and rearwardly along said side walls, tubes connecting said lower water drum and said headers, rows of tubes constituting primary heating elements 35 extending downwardly from said upper drum, the outermost tubes extending downwardly adjacent said side walls, certain of said outermost tubes being connected to said headers and constituting water circulating tubes to assist in providing a 40 constant supply of circulating water for water cooling said side walls and thereby inducing a water circulation in and from the upper drum, while the other outermost tubes and remaining primary heating tubes are connected to said 45 lower drum and constitute water heating and/or steam generating tubes.

11. In a steam boiler, a setting having side 50 walls, an upper water and steam drum, a lower water drum, headers extending forwardly and rearwardly along said side walls, tubes connecting said lower water drum and said headers, rows of tubes constituting primary heating elements 55 extending downwardly from said upper drum, the outermost tubes extending downwardly adjacent said side walls, certain of said outermost tubes being connected to said headers and constituting water circulating tubes to assist in providing a 60 constant supply of circulating water for water cooling said side walls and thereby inducing a 65 water circulation in and from the upper drum, while the other outermost tubes and remaining primary heating tubes are connected to said lower drum and constitute water heating and/or steam generating tubes.

75

- water circulation in and from the upper drum, while the other outermost tubes and remaining primary heating tubes are connected to said lower drum and constitute water heating and/or steam generating tubes, a combustion chamber within said setting forward of said rows of tubes, said headers extending into said combustion chamber, and upcomer steam generating tubes connected to said headers and rising upwardly within said combustion chamber along the side walls thereof and connecting with said upper water and steam drum.
12. In a steam boiler, a setting having side walls, an upper water and steam drum, a lower water drum, headers extending along said side walls, tubes connecting said lower water drum and said headers, rows of tubes constituting primary heating elements extending downwardly from said upper drum, certain of the outermost tubes of said rows of tubes being connected to said headers and constituting water circulating tubes to assist in providing a constant supply of circulating water in and from the upper drum, to and through the headers while the other tubes are connected with the lower drum and constitute water heating and/or steam generating tubes.
13. In a steam generator, a setting having a smoke outlet at the rear thereof, an upper water and steam drum extending the length of said setting, a bridge wall extending transversely of said setting and dividing the interior thereof into a forward combustion chamber and a rear primary heating compartment, a lower water drum within said heating compartment and disposed behind said bridge wall, rows of boiler tubes connecting said upper drum and said lower drum, water wall headers extending along the inside of the side walls of said setting and disposed within said combustion chamber and primary heating compartment, side water wall tubes connecting said headers with said upper drum, and tubes connecting the headers with the lower drum, the rearwardly disposed side water wall tubes connecting said headers and upper drum and the rear rows of boiler tubes constituting down-comers, while the forward water wall tubes and forward rows of boiler tubes constitute upcomers.
14. In a steam generator, a setting, a furnace chamber within said setting having a grate, a water heating and circulating and steam generating system contained entirely within said setting including an upper water and steam drum, opposed water circulating headers extending along the respective side walls of said setting and extending forwardly into said furnace chamber at the grate line thereof and rearwardly of the plane of the front of said lower drum, tubes connecting the lower water drum with the rear portions of said headers, furnace cooling tubes having their lower ends joined to said headers by expanded joints and extending upwardly from said headers with their other ends connected to said upper drum forwardly thereof whereby said headers primarily serve to supply water to the furnace cooling tubes and to secondarily provide a clinker chill at said grate, and a relatively low armor wall disposed inwardly of the side wall of the furnace chamber wall and resting upon that portion of said headers disposed within said furnace chamber and enclosing the lower ends of the furnace cooling tubes to provide a non-clinkering surface.
15. In a steam generator, a setting, a refractory bridge wall extending transversely of said setting to divide the same into a forward combustion chamber and a rear primary heating compartment, an upper water and steam drum extending the length of said setting, a lower water drum disposed within said primary heating compartment, tubes connecting said upper and lower drums, a header extending transversely of said setting adjacent said lower drum, tubes connecting said header with said lower drum, and bridge wall cooling tubes closely associated with said bridge wall and rising upwardly from said header and being connected to said upper water and steam drum, those portions of the bridge wall cooling tubes disposed above the plane of the top of said bridge wall being exposed to the heated gases of combustion as they pass over said bridge wall into said primary heating compartment.
16. In a steam generator, a setting, an upper water and steam drum, a lower water drum, an upstanding refractory bridge wall extending transversely of said setting forward of said lower water drum, and tubes for circulating water from said upper water and steam drum to said lower drum and return, certain of said tubes contacting said refractory bridge wall for a substantial portion of their lengths for water cooling said refractory bridge wall by subjecting the same to the cooling effect of water from said lower water drum during its return to said upper water and steam drum.
17. In a steam generator, a setting, a furnace within said setting forward thereof, a refractory bridge wall at the rear of said furnace and rising from the bottom of said setting, a water heating circulation and steam generating system including an upper water and steam drum, a lower water drum rearwardly of said bridge wall, circulating tubes connecting said upper and lower drums, water circulating headers along opposite sides of said setting extending rearwardly beyond the plane of the front end of said lower water drum, tubes directly connecting opposite sides of said lower drum with said water wall headers rearward of the plane of said bridge wall, superheater tubes extending through said setting and disposed at the rear side of said bridge wall whereby the superheater tubes will be directly swept by the gases of combustion passing rearward from said furnace over the top of said bridge wall and subjected to the heat radiated from said bridge wall, and means connecting the inlet ends of said superheater tubes with the top of said upper drum.
18. In a steam generator, a setting having a forward combustion chamber and a rear heating compartment, a smoke outlet at the rear of said heating compartment, a longitudinal upper water and steam drum, a longitudinal lower water drum within said heating compartment, spaced rows of boiler tubes connecting said upper drum and said lower drum, water wall headers extending along the side walls of said setting and disposed forward and rearward of the plane of the front end of said lower water drum, tubes connecting the rear portions of said headers with opposite sides of said lower drum, means for circulating water from the forward portions of said water wall headers through said combustion chamber to said upper water and steam drum, and spaced overlapping baffles arranged between certain of said rows of boiler tubes for causing the heated gases from said combustion chamber to travel in an undulated path to said smoke outlet.

19. In a steam generator, a setting having a front furnace compartment and a rear heating compartment, an upper longitudinal water and steam drum, a lower longitudinal water drum within said heating compartment, tubes connecting said upper and lower drums, headers disposed along the side walls of said furnace compartment and extending rearwardly beyond the plane of the front end of said lower drum,

tubes connecting the rearwardly extending portions of said headers to opposite sides of said lower drum, upcomer tubes having their lower ends connected to the headers and rising upwardly along the inner side walls of said furnace compartment and their other ends communicating with said upper drum. 5
